PUMP

William E. Pike, Winston-Salem, N. C.

Application August 23, 1932. Serial No. 630,014

6 Claims. (Cl. 103—248)

This invention relates to a pump mechanism for pumping liquid such as water by means of a compressed fluid such as compressed air or steam. The invention relates more specifically to a pump mechanism having an inlet for compressed fluid and outlet for the liquid being pumped, with a float operable by the leveling of the liquid in a suitable chamber for automatically excluding the compressed air and the like from the cylinder 10 while the cylinder is filled with the liquid such as water and for automatically admitting the compressed air and the like to force the liquid such as water upwardly and at the same time closing the intake valve in the cylinder.

15 It is an object of this invention to provide a pump mechanism having a vertically movable float therein for alternately admitting and excluding compressed air from the cylinder and for alternately admitting and excluding the flow 20 of water into the cylinder so that the mechanism is automatic in every detail and is adapted to be placed below the liquid level in a well, tank and the like, so that the pressure of the liquid alternately acting with the operating pressure such 25 as compressed air will tend to automatically operate the pump to elevate the liquid surrounding the pump.

In the description, I have referred to the pump as being operated by compressed air for the 30 pumping of water but it is, of course, evident that this pump may be employed for the pumping of any liquid and any source of fluid under pressure such as steam, compressed air and the like can be used for the motive power.

35 Some of the objects of the invention having been stated, other objects will appear as the description proceeds when taken in connection with the accompanying drawings, in which—

Figure 1 is a side elevation of the pump;

40 Figure 2 is a top plan view of the pump;

Figure 3 is a cross sectional view taken along line 3—3 in Figure 2;

45 Figure 4 is an isometric view of the valve control means for controlling the intake and exhaust of air to and from the pump;

Figure 5 is a transverse sectional view taken along line 5—5 in Figure 1 showing the bottom portion of the pump cylinder;

50 Figure 6 is a vertical sectional view taken along line 6—6 in Figure 5 but showing the valve in an open position;

Figure 7 is a vertical sectional view taken along line 7—7 in Figure 2 showing means for connection of the outlet water pipes to the upper portion 55 of the cylinder;

Figure 8 is a transverse sectional view taken along line 8—8 in Figure 3.

Referring more particularly to the drawings, the numeral 10 indicates a hexagonal base member for the pump which has integral with the lower side thereof vertically disposed supporting members 11, 12, 13 and 14 which are adapted to rest on the bottom of the liquid compartment such as on the bottom of a well.

Hollow cylinder 15 has its lower end mounted 65 in a circular groove in base member 10, and the upper end of cylinder 15 fits into another circular groove in the lower surface of a cylinder head 16. Suitable vertically disposed bolts 17 with a nut on each end pierce the outer edges of the 70 cylinder head 16 and extend downwardly on the outside of cylinder 15 and pierce the outside edges of base member 10 at their lower end. These bolts 17 serve to hold the base 10 and cylinder head 16 and the cylinder 15 together. 75

In the base member 10 a spider member 18 is provided which has slidably mounted therein a bolt 19 which bolt 19 has a smaller threaded portion 20 at its upper end which has threadably mounted thereon a suitable valve cap 21. Upon 80 this smaller threaded portion is mounted a steel washer or the like 22 and a valve washer 23, said washers being confined on bolt 19 by means of valve cap 21, and the shoulder portion of bolt 20. 85

Integral with spider member 18 in base member 10 a circular projection 24 is provided to act as a valve seat and is adapted to contact valve washer 23 when the valve is in a closed position.

90 Directly below spider member 18 and integral with base member 10 downwardly projecting members 25 are provided with a suitable circular plate 26 secured on the lower ends thereof by any suitable means such as screws 27 and around these members 25 a wire mesh 28 is secured to 95 act as a strainer for the water or other liquid before it enters the pump cylinder.

Cylinder head 16 has a hollow housing 29 on the top side which is adapted to contain the valve mechanism 30 for the intake and exhaust of the 100 air to and from the cylinder. This housing has a cover 29a. Valve mechanism 30 is pivoted as at 31 and has a vertically disposed arm 32 which is adapted to contact pin 33 of intake air valve 34 and push it in a position as shown in Figure 3 to allow compressed air from any suitable source to enter the cylinder thru pipe 35, and thru opening around pin 33 into the cylinder. 105 Valve 34 has a suitable valve washer 36 which is adapted to rest against valve seat 37 to cut off 110

the intake supply of air when the valve is closed. A suitable compression spring 38 is adapted to fit in transverse bore 39 and against valve 34. By means of nut 40 which is threadably secured 5 in bore 39, compression spring 38 is held firmly against valve 34 and it is thus seen that by this means pin 33 is normally held at all times in contact with vertically disposed arm 32.

To the left of pivot point 31 a vertically disposed bolt 45 penetrates valve mechanism 30 and is loosely secured thereto by any suitable means such as nuts 46. On the upper end of said bolt 45 is a circular valve cap 47 which has mounted thereon a suitable valve washer 48 which is 15 adapted to contact valve seat 49 to close exhaust opening 50.

On the left end of valve mechanism 30 is pivoted as at 51 a member 52 which projects downwardly into the upper portion of cylinder 15 and 20 laterally almost to the center of the cylinder 15 and then downwardly again until it reaches the lower portion of the cylinder. The lower end of member 52 has a lateral projection 53 which has secured thereto an L-shaped member 54, said member 54 being secured at its lower end as at 55 to arm 56. One end of arm 56 is pivoted as at 57 to U-shaped member 58 and at the other end has pivoted thereto a pin 59 as at 60. Pin 59 has a compression spring 61 therearound, said spring 30 being confined on pin 59 by means of bolt 62 in which pin 59 is slidably mounted. Bolt 62 penetrates U-shaped member 58 at its right hand end in Figures 3 and 5 and is secured thereto by any suitable means such as cotter key 64.

35 U-shaped member 58 has a projection 66 which is secured around the lower portion of water outlet pipe 67. Pipe 67 is threadably secured in the lower end of threaded hole 67a in cylinder head 16, and extends downwardly to a point removed 40 from the base 10. Another pipe 68 is threadably secured in the upper end of hole 67a in cylinder head 16 and has secured on the upper end thereof a check valve 69.

45 Loosely mounted around vertically disposed water outlet pipe 67 and arm 52 is a float 70 which is adapted to be floated in the cylinder by the water and when the cylinder has been filled the float assumes a position as shown in Figure 3. In this position the upper rim 71 of float 70 engages the top lateral portion of arm 52 and causes the left hand end of valve mechanism 30 and also valve cap 47 to move upwardly to close the air exhaust opening 50, and at the same time the vertical arm 32 is simultaneously moved to the right and valve 34 assumes an open position which allows the compressed air to enter the chamber and force the water out thru pipes 67, 68 and check valve 69.

50 When the water has been forced from the cylinder the float 70 falls by gravity and engages the lateral projection 53 of member 52 and forces it downwardly. This action pulls the left hand end of valve mechanism 30 downwardly and causes the reverse operation to take place from that just described, that is, exhaust opening 50 is opened and the intake valve 34 is closed.

55 It will be noted that arm 56, pin 59 and spring 61 mounted in member 58 normally assumes the position as shown in Figure 3 when the cylinder is being filled with water, whereas, when the water has been forced out and the weight of float 70 rests upon lateral projection 53, pivot point 55 suddenly assumes another position as far below a horizontal line thru pivot point 57 as it is now shown above. The above-described arrangement

of arm 56, pin 59 and spring 61 and associated parts provides an off-center snap action or toggle arrangement so that the opening and closing of the intake and exhaust valves will be suddenly executed and thereby provide an efficient opening and closing means.

60 In the drawings and specification, there has been set forth a preferred embodiment of the invention, and although specific terms are employed, they are used in a generic and descriptive sense only, and not for purposes of limitation, the scope of the invention being set forth in the appended claims.

I claim

65 1. In a liquid pump adapted to be operated by compressed fluid such as compressed air and having a chamber, a valve in the lower portion of said chamber thru which the liquid is adapted to flow by gravity, a vertically movable float in said chamber, an air pipe having communication with the upper end of said chamber for admitting compressed air to said chamber, a water pipe having communication with the upper end of said chamber thru which water is adapted to be expelled from said chamber, a double-acting 100 valve for alternately opening and closing the lower end of said air pipe, and off-center snap action means operable by the float for actuating said double-acting valve.

70 2. A pump adapted to be operated by compressed air, steam and the like, a shell member having closures for the lower and upper ends thereof, a valve in the lower closure, a pipe having communication with a source of compressed air and having communication with the upper end of the shell member, a pivoted valve member for intermittently closing and opening the lower end of said pipe to admit compressed air to the shell member, a second pipe for conveying water from the shell member, a float member mounted 115 in said shell member and off-center snap action means operable by the float for actuating said pivoted valve member.

75 3. In a pump for elevating liquids and being adapted to be operated by compressed air, steam and the like, said pump having a chamber adapted to be disposed below the level of the liquid being pumped and being closed at both its ends and having a valve in the lower end and having a pipe conducting compressed air to the upper end, a liquid outlet pipe having connection with the upper end of the chamber, a valve mechanism for intermittently opening and closing said pipe conducting compressed air, a float mounted for vertical movement in said chamber and off-center snap action means operable by said float for operating said valve mechanism for alternately opening and closing said air and liquid pipes.

80 4. In a pump having a chamber and a float in said chamber, valve means for intermittently admitting compressed air to the chamber to expel liquid therefrom, the said chamber being adapted to be submerged below the liquid level to cause the liquid to flow into the chamber when the compressed air is disconnected from said chamber, and off-center snap action means operable by the float for actuating said valve means.

85 5. A compressed air pump having a hollow member closed at both ends, a pipe having connection with a source of compressed air and having connection with the upper end of the hollow member, the upper end of said hollow member having a vent therein, a double acting 150

valve for alternately opening and closing said compressed air pipe and said vent, a float disposed in said hollow member, a valve in the lower end of said hollow member, off-center snap action valve operating means operable by said float when in lowered position to operate said double acting valve to close said compressed air pipe and open said vent, said valve operating means being also operable by said float when in raised position to open said compressed air pipe and close said vent, and a water pipe connected to said hollow member thru which water is adapted to be expelled by the compressed air.

6. In a pump having a casing adapted to be disposed below a liquid to be pumped, said casing having a valve in the lower end thereof

thru which the liquid is adapted to flow by gravity into said casing, a pipe for conducting compressed air to the upper end of said casing, a vent in the upper end of said casing, a valve mechanism for alternately opening and closing communication between said chamber and said compressed air pipe and said vent, a liquid exhaust pipe connected to said casing, a float disposed in said casing, off-center snap action means engageable by said float for operating said valve mechanism to intermittently admit and exhaust compressed air into and from said casing to force the liquid from said casing thru said liquid exhaust pipe.
